UNITED STATES PATENT OFFICE.

SAMUEL E. TOOLEY, OF CAZENOVIA, NEW YORK.

DESIGN FOR A KITCHEN-CABINET.

SPECIFICATION forming part of Design No. 27,909, dated November 30, 1897.

Application filed September 15, 1897. Serial No. 651,779. Term of patent 14 years.

To all whom it may concern:

Be it known that I, SAMUEL E. TOOLEY, a citizen of the United States, residing at Cazenovia, in the county of Madison, in the State 5 of New York, have invented and produced a new and original Design for Kitchen-Cabinets, of which the following is a specification, reference being had to the accompanying drawing, in which I show a perspective view 10 thereof, this view being deemed sufficient to fully illustrate my design.

As shown in the accompanying drawing, the leading feature of my design consists in a kitchen-cabinet adapted to receive and hold 15 various articles of food—such as flour, meal, spices, &c.—as a unitary article.

The cabinet comprises end pieces or uprights *a*, a back *a'*, and a front *b*, extending part of the way up, the upper portion of the 20 uprights being cut rearwardly, as shown at *b*, and a door *c*, hinged horizontally at the top of the front *b* and adapted to rest, when closed, upon the removed portion of the uprights *a*. The upper end of the uprights *a* are cut so as 25 to slant rearwardly, as shown at *c'*, and the

back *a'* extends beyond the said uprights and terminates, as shown at *d*. At the top of the uprights *I* secure a cross-piece *e*, the upper edge of which is of some fanciful design, as shown at *e'*. The base or the lower ends of 30 the said uprights *a* are cut out in some fanciful form, as shown at *f*.

The interior of the cabinet is divided up into large compartments in the bottom for flour, meal, &c., while the portion above this 35 is divided up into compartments *g*.

h is a chain or flexible support connecting the lid with the side pieces, as shown.

Having described my invention, what I claim, and desire to secure by Letters Patent, is—

The design for a kitchen-cabinet, substantially as herein described and shown.

In witness whereof I have hereunto set my hand this 11th day of September, 1897.

SAMUEL E. TOOLEY.

In presence of—

MARY A. FRANKLIN,
HOWARD P. DENISON.
